GARMENT WITH ADJUSTABLE COLLAR

Ciro Merola, Bayonne, N. J.

Application December 2, 1941, Serial No. 421,261

7 Claims. (Cl. 2-98)

This invention relates to improvements in coats or jackets.

It is an object of the present invention to provide a coat or jacket with a collar, the length of which may be adjusted after the coat has been manufactured, to suit the neck height of the wearer.

It is another object of the present invention to provide for the said collar adjustment without requiring material to be removed or added to the manufactured coat.

It is a further object of this invention to provide a manufactured coat in which the collar and lapel portions are integral with the front portions of the coat, and in which the collar may be raised or lowered in a simple and expeditious manner to conform to the neck-height of the wearer.

It is a still further object of the present invention to provide a garment wherein the back portion thereof is free of direct connection from the collar body of the garment and wherein a member is secured to the collar body and the back portion whereby severance of the member from either the collar body or back portion will permit the collar body to be raised and lowered relative to the back portion.

Other objects and advantages of the invention will appear as the description proceeds, it being understood, however, that it is not intended that the invention be limited to the exact details described herein which illustrates the production of one satisfactory product of many which may be obtained as a result of the knowledge gained through or gleaned from an understanding of the invention; and it is further intended that there be included, as part of the invention all such obvious changes and modifications thereof as would occur to a person skilled in the art to which this invention pertains and as would fall within the scope of the claims.

In the drawings:

Fig. 1 is a plan view of the left front portion of a garment to which the invention is applied;

Fig. 2 is a plan view of the right front portion thereof;

Fig. 3 is a plan view of the left rear portion thereof;

Fig. 4 is a plan view of the right rear portion thereof;

Fig. 5 is a plan view of a filler piece or member employed in the invention;

Fig. 6 is a view of the left front and rear pieces of the garment in assembled condition;

Fig. 7 is an enlarged detail view showing the

construction at the rear upper part of the garment observed from the outside of the garment, the member of Fig. 5 being shown partly folded back;

5 Fig. 8 is a sectional view of Fig. 7 taken at line 8-8 thereof; and

Fig. 9 is a sectional view similar to Fig. 8 but showing the slot in expanded position in accordance with the invention.

The numerals 15, 16, 17, 18 indicate the four panels or portions in making up a conventional coat or jacket. The portions or panels 15, 16 are connectable at the front of the garment. The numerals 19 and 20 indicate the lapel portions 15 of the coat, while 21 and 22 indicate the integral collar portions of the collar body forming extensions thereof. Slits 23 and 24 are cut at the point of juncture of the collar portions 21 and 22 with the coat portions 15 and 16, respectively. These 10 cuts or slits 23, 24 are disposed below the collar fold line (see Fig. 6) separating the collar body from the portions 15, 16 at substantially the shoulder of the garment. The shoulders of the coat are formed by connecting seam edge 25 with seam edge 26, and seam edge 27 with seam edge 28. Both back pieces 17 and 18 have extensions 29 and 30 for connection with the flat flexible member or filler piece 33 by the seams 43 (Figs. 7 and 9). These extensions are adjacent to collar 15, 16 at substantially the shoulder of the garment. The sleeves fit into cuts 34, 35 and 36, 37 of the respective pieces 15 to 18, inclusive. These pieces are also sewed along lines 38 to 43 inclusive, during construction 15 of the garment. When these portions are assembled, they will form sleeve openings 44 and 45.

As clearly shown in Fig. 7 when all of the aforementioned portions are joined together to form the garment, there may be provided below the collar 21, 22 an opening or cut-out comprising the notched-like end portions 46a and the narrower intermediate longitudinal portion or slit 46. The extensions 29, 30 are free of direct connection from the collar body extensions 31, 32.

45 The space 46 in Figs. 7 and 8 can be enlarged as at 47 (Fig. 9) by removing either stitches 48 or 49 and then resewing member 33. Thus the collar may be raised or lowered relative to the back portion of the garment. The coat collar when normally turned down covers strip 33.

The invention is particularly adapted for use in connection with manufactured garments sold to the consumer through retail outlets. In this case, the stitches 49 may be of such nature as to be easily removed. If a person having a long

neck is to be fitted by the retailer, these stiches 49 are removed, the collar raised (since it is disconnected from the back portion of the garment) and member 33 restitched. Referring particularly to Figs. 7-9 this means that portions 29, 30 and 31, 32 are spread apart to suit the neck height of the wearer before sewing down the member 33 by means of stiches 48, 49. Now, in case a wearer having a low neck is to be fitted, the parts 29, 30, and 31, 32, are brought closer together to again suit the particular neck height of the wearer before the member 33 is secured by means of stiches 49.

Referring to the foregoing embodiment, it is evident that in its more specific aspect, the invention includes a garment comprising connectable front sections having body portions 15, 16 and lapels 19, 20 provided, respectively, with connected extensions 21, 22 constituting a collar body for the garment the said sections having the slits 23, 24 forming cuts 46a at the body portions separating the collar body from the body portions at substantially the shoulders of the garment, the back of the garment (which may comprise the two connected panels 17, 18), having its upper portion including extension 29, 30 free of direct connection from the collar body or the collar extensions 31, 32 and the flat flexible strip or member 33 overlying the cuts 46a and the upper portion of the back, member 33 being secured to the collar body and to the upper portion of the back and to the front sections 15, 16.

This application is a continuation in part of my earlier application, Serial No. 379,863, filed February 20, 1941, for Coat with an adjustable collar.

Having thus described my invention, what I claim as new and desire to secure by Letters Patent, is:

1. In a garment, two sections connectable at the front, a collar body for said garment, said collar body connecting with said sections and having a fold line, a back for said garment having its upper portion free of direct connection from said collar body, and a flat flexible member secured to said collar body adjacent said fold line and to said upper portion, whereby severance of said securing means will permit said collar body to be moved relative to said back.

2. In a garment, a body including a back portion, a collar body for said garment, said back portion being free of direct connection from said collar body, and a member secured to said collar body and to said back portion, whereby severance of said member from either said collar body or said back portion will permit said collar body to be raised or lowered relative to said back portion.

3. In a garment, a body including two sections connectable at the front and a back portion, a collar body for said garment, said back portion and a portion of each of said sections

being free of direct connection from said collar body, and a member secured to said collar body and to said back portion and said sections, said collar body being movable relatively to said back portion prior to said securing of said member.

4. In a garment, a collar structure and a body, said body including a back, said back being free of direct connection from said collar structure whereby they are relatively movable, and a member attachable to said collar structure and said back for maintaining the position between said collar structure and said back upon said relative movement.

5. In a garment, a collar structure and a body, said body including two panels connectable at the front of the garment and a back intermediate said panels, each of said panels including a lapel having an extension forming part of said collar structure, said back being free of direct connection from said extensions and each of said panels being slit adjacent said extensions whereby said extensions are movable with relation to said back and the portions of said panels separated from said extensions by said slits, and a flat member adapted to overlie said slits and attachable to said collar structure, said back and said panels.

6. In a garment two connectable front sections, each of said sections including a body portion and a lapel having an extension, said extensions being connected constituting a collar body for the garment, said collar body having a fold line, each of said front sections having a cut below said fold line and at said body portion separating said collar body from said body portion at substantially the shoulder of the garment, a back for said garment having its upper portion free of direct connection from said collar body, and a flat flexible member overlying said cuts and said upper portion and being secured to said collar body adjacent said fold line and to said upper portion and said body portions, said collar body being movable relatively to said body portions at said cuts and to said upper portion prior to securing of said member.

7. In a garment two connectable front sections, each of said sections including a body portion and a lapel having an extension, said extensions being connected constituting a collar body for the garment, each of said front sections having a cut at said body portion separating said collar body from said body portion at substantially the shoulder of the garment, a back for said garment having its upper portion free of direct connection from said collar body, and a flat member overlying said cuts and said upper portion and being secured to said collar body and to said upper portion and said body portions, said collar body being movable relatively to said body portions at said cuts and to said upper portion prior to securing of said member.

CIRO MEROLA.
